(57) **CLAIM**

We claim the ornamental design for a generator, as shown and described.

DESCRIPTION

FIG. 1 is a top, front, left side perspective view of a first embodiment of a generator showing our new design; FIG. 2 is a top, rear, left side perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is a top, front, right side perspective view of a second embodiment of a generator showing our new design; FIG. 10 is a top, rear, right side perspective view thereof; FIG. 11 is a front elevation view thereof; FIG. 12 is a rear elevation view thereof; FIG. 13 is a left side elevation view thereof; FIG. 14 is a right side elevation view thereof; FIG. 15 is a top plan view thereof; and, FIG. 16 is a bottom plan view thereof.

The broken lines shown in the views are included for the purpose of illustrating portions of the generator that form no part of the claimed design.

1 Claim, 16 Drawing Sheets
